DENTAL ARTICULATOR

Wayne W. Moore, Chicago, Ill.

Application July 1, 1946, Serial No. 680,701

9 Claims. (Cl. 32—32)

1

The present invention relates to improvements in dental articulators.

It is an object of my invention to provide a dental articulator which is of simple, inexpensive, and sturdy construction, and which yet provides for ascertaining whether a denture, either complete or partial, or complete or partial upper and lower dentures, are in proper alignment with respect to a model or models of remaining natural teeth or of the dentures with respect to each other, respectively, and for simulating the movement of teeth in mastication. More specifically, it is an object of my invention to provide lower and upper denture supporting members arranged in spaced apart relation with the upper member surmounting the lower member, with means being provided for pivotally mounting the members together adjacent their rearward ends, and with means being provided for normally maintaining the pivoted relationship of these members, which latter means is yieldable to enable relative general lateral movement, simulating the movement of mastication, of the members with respect to each other. Still more specifically, it is an object to provide in a device as aforesaid adjustable means for limiting pivotal movement of the upper denture supporting member toward the lower denture supporting member.

A preferred structural feature of my invention resides in the provision of a lower denture supporting member comprising an integral supporting means at the rearward end thereof having a pair of spaced upstanding arms connected adjacent their upper ends by a transversely extending frame member, and in which the upper ends of the arms are slotted to receive pin means at the rearward end of the upper denture supporting member to provide a pivotal mounting thereof.

A further preferred feature resides in the provision of spring loaded jaw members adapted to be pivotally supported on the frame member of the lower denture supporting member for normally yieldingly engaging the upper denture supporting member to maintain the pin means of the latter in the slots of the lower denture supporting member, and which jaw members provide for general relative lateral movement of the upper and lower members with respect to each other.

A further preferred feature resides in the provision in a device as aforesaid of screw means

2

threaded in the frame member of the supporting means of the lower denture supporting member adapted to engage a rearwardly extending tongue of the upper denture supporting member for adjusting the limit of its pivotal movement toward the lower denture supporting member.

A further preferred feature is in providing in a device as aforesaid a cored chamber in the frame member of the lower denture supporting member in which the spring loaded jaws are pivotally mounted, and between which the aforesaid screw means extends through the chamber, there being a sleeve disposed about the screw means in the chamber about which a coil spring is positioned with the opposite ends of the coil spring engaging the jaws to provide the spring loading thereof.

A still further preferred feature is in the provision of a construction in which the spring loaded jaws are of identical form, facilitating the making thereof and their assembly in the device.

Other objects, features, and advantages of my invention will appear from the detail description.

Now in order to acquaint those skilled in the art with the manner of constructing and utilizing a device in accordance with my invention, I shall describe in connection with the accompanying drawings a preferred embodiment of my invention.

In the drawings:

30 Figure 1 is a side elevational view of a device constructed in accordance with my invention;

Figure 2 is a right hand end view of the device of Figure 1;

Figure 3 is a detail vertical sectional view taken on the line 3—3 of Figure 2, looking in the direction indicated by the arrows, with certain of the parts being shown in elevation;

Figure 4 is a plan view of the device of Figures 1 and 2;

40 Figure 5 is a plan view of the upper denture supporting member of the device of Figures 1, 2 and 4; and

Figure 6 is a plan view of the device of Figures 1 and 2 illustrating the position of the upper dental supporting member shifted generally laterally in one direction relative to the lower denture supporting member to simulate the action of mastication.

Referring now to the drawings, it will be seen that I have provided a dental articulator com-

prising a lower denture supporting member 7 and an upper denture supporting member 8 spaced from and surmounting the lower denture supporting member 7. The members 7 and 8 are adapted to support lower and upper dentures 9 and 10, respectively, in the position they would assume in a patient's mouth. The members 7 and 8, as more clearly shown in Figures 4 through 6, are formed with a plurality of openings 11 to provide a plurality of ribs and narrow marginal edges therein which are adapted to be embedded in suitable jaw molding material 12 such as plaster of Paris, for mounting the dentures 9 and 10 upon the denture supporting members.

It will be understood that while I have shown complete upper and lower dentures mounted in the device that the upper and lower frames may provide for the support of partial dentures on a model or models of the remaining natural teeth of a patient, the word "denture" as herein used should be construed in this sense.

It will be observed that a supporting means 13 is formed integrally with the lower denture supporting member 7 and it comprises a pair of spaced arms 14-14 extending vertically upwardly of the rearward end of the lower member 7 from opposite sides thereof with the upper ends of the arms 14-14 being connected together by the arcuate generally transversely extending frame member 15 preferably formed integrally therewith. The frame member 15 centrally thereof is formed with an enlarged portion 16 having a cored chamber 17 opening forwardly and rearwardly and having an upper wall 18 and a bottom wall 19. The vertically extending arms 14-14 at their upper ends each have a slot 20 formed in the ears 21 integral with the arms, and which slots extend generally forwardly and slightly downwardly as best shown in Figures 1 and 3.

The upper denture supporting member 8 adjacent its rearward end is formed with an integral substantially cylindrical end portion 22 having laterally extending cylindrical end extensions 23-23 in which the pivot pins 24-24 are secured. A tongue 25, also preferably integral with the upper denture supporting member 8, extends rearwardly thereof, terminating below the chamber 17 when the pivot pins 24-24 are disposed in slots 20-20 in the ears 21-21. The outer ends of the cylindrical extensions 23-23 are rounded as shown at 26 to provide for slight rocking movement with the adjacent inside surfaces of ears 21-21 in the general lateral movement of the denture supporting members as referred to more in detail hereinafter.

A pair of jaw members 27-27 are pivotally mounted in chamber 17 about vertically extending pivot pins 28-28, the upper and lower ends of which are suitably secured in the upper and lower walls 18 and 19. A screw 29 having a knurled upper end 30 has threading engagement with the upper and lower walls 18 and 19 and extends vertically through the chamber 17 between the pivot pins 28-28 for the jaws 27-27. As shown more clearly in Figure 3, a sleeve 31 is disposed in chamber 17 between the upper and lower walls thereof and through which the threaded shank of screw 29 extends. The lower end of screw 29 is rounded and engages the rearwardly extending tongue 25 of the upper denture supporting member to adjust the limit of pivotal movement of the latter about the pivot pins 24-24 in slots 20-20 toward the lower denture supporting member. A coil spring 32 is disposed

about the upper shank portion of the screw 29 between washers 33-33 adjacent the knurled upper end 30 and the upper surface of the upper wall 18 defining chamber 17 to prevent accidental turning of screw 29.

A coil spring 35 is arranged coaxially of sleeve 31 and the upper and lower free ends thereof are extended to engage in slots 37-37 formed in the inside surfaces of the jaws rearwardly of the pivotal mountings thereof to normally bias the jaw members about their pivots to engage the arcuate forward ends 38-38 of the jaws with the cylindrical extensions 23-23 of the lower denture supporting member 8 to yieldingly retain the pivot pins 24-24 of the latter in slots 20-20. The jaw members 27-27 at their rearward ends are formed with finger grip portions 40-40 which when grasped and urged toward each other swing the forwardly extending ends of the jaws away from the cylindrical extensions 23-23 against the face of coil spring 35 whereupon the upper denture supporting member may be readily disassembled from the lower denture supporting member. It is to be observed that the jaw members 27 are of identical construction with the grooves 37 formed therein either being disposed upwardly or downwardly when assembled on the pivot pins therefor in the chamber 17 for reception of the upper and lower extensions of coil spring 35, respectively.

In Figures 1, 3, 4 and 6 it will be observed that the upper edges of the transverse frame member 15 adjacent their junction with the upstanding arms 14-14 are formed with cam surfaces 41-41 extending generally rearwardly and slightly upwardly of the lower edges of slots 20-20.

It is believed it will be apparent with the construction above described that the spring loaded jaw members 27-27 normally maintain the pivot pins 24-24 of the upper denture supporting member 8 in the slots 20-20 of the lower denture supporting member 7 for pivotal movement of the upper member 8 about the horizontal axis of the pivot 24-24 with the pivotal movement of the upper member 8 being limited by engagement of the tongue 25 thereof with the bottom semispherical end of the screw 29. With the parts in this position the spring loaded jaw members 27-27 permit general lateral movement of the upper and lower denture supporting members with respect to each other, as shown in Figure 6, and during which lateral movement the pivot pins 24-24 in following the cam surfaces 41-41 simulate the movements of the human jaws in mastication. The rounded ends 26-26 of the cylindrical extensions 23-23 maintain to a minimum frictional engagement with the adjacent inside surfaces of ears 21-21 and facilitate the lateral movement of the upper and lower denture supporting members with respect to each other. For convenience in handling the device, I preferably provide the outer edges of the upstanding arms 14-14 with recesses 43-43 which are of suitable shape to be grasped in one hand whereby the aforesaid movements of the upper and lower denture members with respect to each other may be readily accomplished.

While I have shown and described what I consider to be a preferred embodiment of my invention, it will be understood that various modifications may be made therein without departing from the spirit and scope of my invention.

I claim:

1. A dental articulator comprising a lower denture supporting member, an upper denture sup-

porting member adapted to be spaced from and surmount said lower denture supporting member, said lower member having integral upstanding supporting means at the rearward end thereof provided with generally forwardly extending slots, pivot pin means on said upper member lying on an axis extending transversely of the rearward end of the latter and adapted to be disposed in said slots, and a pair of spring loaded jaws individually pivotally mounted on said supporting means rearwardly of said slots and normally biased into engagement with said upper member to maintain normally said pivot pin means in said slots, said jaws being bifurcated at their forward ends engaging said upper member and provided with handle portions at their opposite ends for individually or simultaneously retracting said jaws.

2. A dental articulator comprising, a lower denture supporting member, an upper denture supporting member adapted to be spaced from and surmount said lower denture supporting member, said lower member having integral upstanding supporting means at the rearward end thereof provided with generally forwardly extending slots, pivot pin means on said upper member lying on an axis extending transversely of the rearward end of the latter and adapted to be disposed in said slots, a pair of spring loaded jaws individually pivotally mounted on said supporting means rearwardly of said slots and normally biased into engagement with said upper member to maintain normally said pivot pin means in said slots, said upper member having a rearwardly extending tongue, and adjustable screw means carried by said supporting means for engaging said tongue of said upper member for limiting pivotal movement of the latter toward said lower member, said jaws being bifurcated at their forward ends engaging said upper member and provided with handle portions at their opposite ends for individually or simultaneously retracting said jaws.

3. A dental articulator comprising, a lower denture supporting member, an upper denture supporting member adapted to be spaced from and surmount said lower denture supporting member, said lower member having integral supporting means at the rearward end thereof comprising a pair of spaced upstanding arms connected together adjacent their upper rearward portions by a transversely extending frame member, said arms at their upper ends each having a generally forwardly extending slot, pivot pin means on said upper member lying on an axis extending transversely of the rearward end of the latter and adapted to be disposed in the slots of said arms, a pair of jaws individually pivotally mounted on said frame member between said arms, spring means for normally biasing said jaws into engagement with said upper member to retain yieldingly said pivot pin means in said slots, said jaws being bifurcated at their forward ends engaging said upper member and provided with handle portions at their opposite ends for individually or simultaneously retracting said jaws, said upper member having a rearwardly extending tongue, and screw means carried by said frame member intermediate the pivotal mountings of said jaws for engaging said tongue.

4. A dental articulator comprising, a lower denture supporting member, an upper denture supporting member adapted to be spaced from and surmount said lower denture supporting member, said lower member having integral supporting means at the rearward end thereof com-

prising a pair of spaced upstanding arms connected together adjacent their upper rearward portions by a transversely extending frame member, said arms at their upper ends each having a generally forwardly extending slot, pivot pin means on said upper member lying on an axis extending transversely of the rearward end of the latter and adapted to be disposed in the slots of said arms, said frame member having a chamber formed therein, a pair of jaw members pivotally intermediate their ends in said chamber about pivot pins extending vertically through said chamber, said jaw members being formed at their forward ends with portions for engaging said upper member and at their rearward ends with finger grip portions for individually or simultaneously retracting said forward end, said upper member having a rearwardly extending tongue underlying the chamber of said frame member; a screw threaded in said frame member and extending through the chamber thereof between the pivot pins for said jaw members for engaging said tongue of said upper member, a sleeve coaxial of said screw and disposed in said chamber, and a coil spring coaxial of said sleeve and having its opposite ends in engagement with said jaw members for normally urging the forward portions thereof into engagement with said upper member.

5. A dental articulator comprising, a lower denture supporting member, an upper denture supporting member adapted to be spaced from and surmount said lower denture supporting member, said lower member having integral supporting means at the rearward end thereof comprising a pair of spaced upstanding arms connected together adjacent their upper rearward portions by a transversely extending frame member, said arms at their upper ends each having a generally forwardly extending slot, cam surfaces extending rearwardly and upwardly from the lower edges of said slots, pivot pins on said upper member projecting laterally from the sides thereof on an axis extending transversely of the rearward end of said upper member and adapted to be disposed in the slots of said arms, a pair of jaws individually pivotally mounted on said frame member between said arms and individually or simultaneously retractable, and spring means for normally biasing said jaws into engagement with said upper member to retain normally said pivot pins of said upper member in said slots, said upper and lower members being movable generally laterally with respect to each other with the pivot pins in engagement with said cam surfaces and against the force of said spring.

6. A dental articulator comprising, a lower denture supporting member, an upper denture supporting member adapted to be spaced from and surmount said lower denture supporting member, said lower member having integral supporting means at the rearward end thereof comprising a pair of spaced upstanding arms connected together adjacent their upper rearward portions by a transversely extending frame member, said arms at their upper ends each having a generally forwardly extending slot, cam surfaces extending rearwardly and upwardly from the lower edges of said slots, pivot pins on said upper member projecting laterally from the sides thereof on an axis extending transversely of the rearward end of said upper member and adapted to be disposed in the slots of said arms, a pair of jaws individually pivotally mounted on said frame members between said arms and individually or

simultaneously retractable, spring means for normally biasing said jaws into engagement with said upper member to retain normally said pivot pins of said upper member in said slots, said upper and lower members being movable generally laterally with respect to each other with the pivot pins in engagement with said cam surfaces and against the force of said spring means, said upper member having a rearwardly extending tongue, and adjustable screw means carried by said frame for engaging said tongue of said upper member for limiting pivotal movement of the latter toward said lower member.

7. A dental articulator comprising, a lower denture supporting member, an upper denture supporting member adapted to be spaced from and surmount said lower denture supporting member, said lower member having integral supporting means at the rearward end thereof comprising a pair of spaced, upstanding arms connected together adjacent their upper rearward portions by a transversely extending frame member, said arms at their upper ends each having a generally forwardly extending slot, cam surfaces extending rearwardly and upwardly from the lower edges of said slots, pivot pins on said upper member projecting laterally from the sides thereof on an axis extending transversely of the rearward end of said upper member and adapted to be disposed in the slots of said arms, a cored chamber in said frame member forming forwardly and rearwardly thereof, a pair of jaw members individually pivoted intermediate their ends in said chamber about pivot pins extending vertically therethrough and projecting through the forward and rearward openings thereof, said jaw members being formed at their forward ends with portions for engaging said upper member and at their rearward ends with finger grip portions for individually or simultaneously retracting said jaw members against the action of a spring means tending to force their forward ends into engagement with said upper member, said upper member having a rearwardly extending tongue underlying the chamber of said frame member, a screw vertically threaded in said frame member extending through the chamber thereof between the pivot pins for said jaw members for engaging said tongue of said upper member, a sleeve coaxial of said screw and disposed in said chamber, and a coil spring coaxial of said sleeve and having its opposite ends in engagement with said jaw members for normally urging the for-

ward portions of the latter into engagement with said upper member.

8. Means for yieldingly maintaining upper and lower denture supporting members of a dental articulator in pivotal relation about pivot means provided therebetween comprising, a pair of jaw members individually pivotally mounted intermediate their ends on spaced pivot pins supported by said lower member, said jaw members having portions at one of the ends thereof for engaging said upper member and finger grip portions at their other ends for individually or simultaneously retracting said jaw members from engagement with said upper member, and a coil spring supported by said lower member between said jaws with the opposite ends of the coil spring in engagement with said jaw members and normally biasing the latter to engage the said one ends thereof into engagement with said upper member.

9. Means for yieldingly maintaining upper and lower denture supporting members of a dental articulator in pivotal relation about pivot means provided therebetween comprising, a pair of jaw members pivotally mounted intermediate their ends on spaced pivot pins supported by said lower member, said jaw members having portions at one of the ends thereof for engaging said upper member and finger grip portions at their other ends, a screw threaded in said lower member intermediate the pivot pins of said jaw members, a sleeve coaxial of said screw and disposed between said jaws, and a coil spring coaxial of said sleeve with the opposite ends of said coil spring in engagement with said jaw members and normally biasing the latter to engage the said one ends thereof into engagement with said upper member.
